UNITED STATES PATENT OFFICE.

FREDERICK WILLIAM WAGGETT, OF LONDON, ENGLAND.

PIANOFORTE ACTION.

Application filed May 3, 1923, Serial No. 637,587, and in Great Britain August 4, 1922.

This invention relates to pianoforte actions.

The invention has for one of its objects to provide an improved pianoforte action having means whereby the co-operation between the "fly" or "jack" and the hammer are rendered more positive and at the same time more delicate, the sensitiveness to movement of the hammer in response to the operation of the key is increased, and the action as a whole can be operated and the instrument played much more rapidly than heretofore.

Another object of the invention is to provide means whereby a greater unity or more positive co-operation is obtained between the key and the lower part of the action.

Still another object of the invention is to provide improved means for "setting off" the "fly" or "jack" and to prevent excessive raising or operation of the action.

According to one feature of the invention the "fly" or "jack" and the portion of the hammer with which said "fly" or "jack" engages are operatively and positively connected to one another by means of a finger or projection provided on the one and engaged within an aperture or loop provided on the other.

Another feature of the invention consists in that the connection above described is such that after the "fly" or "jack" has been operated to throw the hammer on to the strings, and when it is "set off", it recedes and "checks" or holds the hammer in situ and its partly retracted position so long as the key is depressed, and then pulls or helps to positively move the hammer back to its normal fully retracted position when the key is released, thus dispensing with the necessity for the employment of the usual "check", "check-hammer", "tape", "tape-wire", and guard or "slap rail".

According to yet another feature of the invention the key and the lower part of the unit of the action which said key engages may be positively interconnected or movably interlocked with one another.

Still another feature of the invention consists in that mechanical means may be provided for positively causing the "setting off" and receding movement of the "fly" or "jack" into its position in which it "checks" the hammer.

The invention will now be described with

reference to the accompanying drawings, in which:—

Figure 1 illustrates diagrammatically three suitable shapes of the hammer-butt aperture;

Figures 2 to 5 shew five convenient constructions of the upper end of the "fly";

Figures 6 and 7 are detail side elevations illustrating suitable methods of applying the invention to wooden and metal actions, respectively;

Figure 8 shows in perspective a modified form of aperture member.

Figure 9 is a perspective view illustrating a flexible form of aperture member.

Figure 10 is a side elevation of a complete wooden action unit and showing a further modified method of carrying out the invention, and

Figure 11 is an enlarged detail perspective view of several of the parts shown in Figure 10;

Figure 12 is a side elevation illustrating the invention applied to a complete metal action unit;

Figure 13 is a front elevation of said unit; and

Figure 14 is a perspective view of the "set off" of Figures 12 and 13;

Figure 15 shows another modified form of the apertured member;

Figure 16 illustrates in perspective suitable means for causing a positive co-operation between a key and its corresponding action unit;

Figure 17 is a perspective view of convenient means for retracting the "jack."

Figure 18 is a view in elevation, partly in section, illustrating the application of the construction as shown in Figure 16.

In all of the figures similar parts are designated by like reference numerals.

In a suitable manner of carrying out the invention the hammer-butt may be provided with an aperture and the upper end of the "jack" can be arranged to engage within said aperture in such manner as to bring about the operations above mentioned. The aperture may be of such shape that it provides a projection against which the upper end of the "jack" operates in the usual manner to throw the hammer on to the strings, and that it has an extended portion which receives the upper end of the "jack" when the latter is "set-off," this portion of the

aperture being of such shape that it allows the said upper end of the "jack," which upper end is preferably of similar shape to the aperture at this portion, to hold the hammer more or less firmly in partly retracted position after the strings have been struck by the hammer. In the accompanying drawings, Figure 1 indicates three suitable shapes of the aperture at 20, 21 and 22, 10 the projection within the aperture being indicated at 23 and the part of said aperture into which the "jack" recedes being shown at 24; the lower portions or the aperture indicated by dotted lines may be omitted, particularly when the aperture is 15 formed in solid material such as in the base of a wooden hammer-butt. The upper end 27 of the "jack" may be provided with a finger or projection 28 shaped to correspond 20 with the particular shape of the aperture; the fingers of the "jacks" shown in Figures 2 and 6 are shaped to correspond and co-operate with an aperture such as that indicated at 20 in Figure 1. The upper end of the 25 "jack" may be provided with a support at one or each side of the finger or projection 28. Thus, in Figures 2, 4 and 5 one support is provided at 29, and in Figures 3 and 4 two supports are illustrated at 29'. The 30 upper end 27 of the "jack," with or without the finger or projection thereof, may be made of cast, stamped or pressed sheet metal or of metal wire and be fitted to a wooden "jack" body as 30 in Figure 6, or it can be formed 35 integrally with the body of the "jack" such as shown in Figure 7. The requisite size and shape of the finger or projection 28 may be obtained by fitting a piece of wood, leather, india-rubber, felt or the like upon the metal upper end 27 of the "jack," as in 40 Figures 6 and 7, or the metal itself may be bent or otherwise formed to the required size and shape, such as indicated in Figures 2 and 5. If desired a piece of wood, leather, 45 india-rubber, felt or the like may be fitted by means of a pin or otherwise between the supports 29' of Figures 3 and 4.

The aperture of the hammer-butt with 50 which the finger or projection 28 of the "jack" co-operates may be formed in or applied to said hammer-butt in various ways; thus, as indicated in Figure 6, the aperture may be cut out transversely of the wood base of said hammer-butt or it may be obtained 55 by bending or otherwise shaping a piece of metal wire or strip to the requisite shape and fixing same to the wooden hammer-butt. This metal piece may be in the form of a screw-hook, the wood of the butt forming 60 the projection with which the "jack" co-operates, or the said metal piece may be made as shown at 31 in Figure 8 and be secured to the wood by a screw 32 or in any other suitable manner. In a metal action 65 the aperture may be formed by suitable

bending or shaping a portion of the hammer-butt or a separate member attached thereto, such as indicated at 33 in Figure 7 and Figure 12. If desired the aperture may be lined with leather, felt, cloth, india-rubber 70 or the like to avoid noise in working, in place of, or in addition to, similar material applied to the finger or projection at the upper end of the "jack" as above mentioned. The soft material may be held in place by means 75 of an adhesive, by threading or winding the same upon the finger or projection, or by means of staples or the like, or it can be sewn in position, or the metal may be bent to form a clip which is pressed down upon 80 the material to clamp the same; such a form of clip is indicated at 34 in Figure 8.

Figures 6 and 7 show the invention applied to wooden and metal actions, respectively, and indicate the hammer-butt 26 and 85 the "jack" 27, 30 in position for striking the strings. The key, when operated, raises the "jack" in usual manner and the latter throws the hammer 26 forward owing to the finger or projection 28 on said "jack" pushing against the projection 23. At a given moment the "set-off" 35 is reached and the latter operates the heel 36 of the "jack", and the finger or projection 28 is thereby caused to move into the extended portion 24 95 of the aperture, in which position the hammer is "checked" from rebounding to the strings, and is also held in position away from the strings until the key is released, when the "jack", falling with the lower 100 portion of the action with which said key co-operates, pulls or assists the movement of the hammer back to its normal position, the "jack" being caused to resume its normal position for the next blow by means of 105 its usual control spring.

In a modified construction, and as indicated in Figure 9, the aperture may be formed by a piece of leather or other flexible material 37 attached to the base 25 of 110 the hammer-butt. The flexible material may be used by itself or it may be disposed within a guide such as 38.

In another modification, Figures 10 to 13 and 15, the aperture may be oval in shape 115 and the finger or projection 28 at the upper end of the "jack" may be more or less circular. With this construction, normally the finger 28 rests in the portion 39 of the oval member 40, and when the key 41 is 120 operated said finger 28 engages the upper portion 42 of the oval and throws the hammer 43 on to the strings 44; when the blow has been struck the finger 28 is moved to the other end 45 of the oval 40 by the action 125 of the "set-off" 35 upon the heel 36 of the "jack", so that the hammer is "checked" and held in situ away from the strings 44 and until the key 41 is released. This construction of the aperture, and the absence 130

of the projection 23 of the forms of the invention first described, enables the blow of the hammer to be repeated without the necessity of the key fully reaching its upper 5 normal position.

If desired means, such as an adjustable screw 46, Figure 15, may be provided on the aperture member 40 to protrude into the aperture to vary the movement of the 10 finger 28 of the "jack" therein, or a piece of spring steel or the like 49 may be adjustably fitted inside the aperture member for the same purpose, or in the case when the aperture is formed within a stamped metal 15 strip or like member the said member may be adjustable in size.

To obtain a greater unity or more positive co-operation between the key and the lower part of the action with which the said key 20 engages, the key-carriage 50 and the portion 51 of said lower part of the action which normally rests thereon may be interconnected or movably interlocked with one another in a suitable manner; for instance, 25 one of the parts may be forked or bifurcated and the other be provided with a part adapted to fit loosely over and under the fork or bifurcation. In Figure 16 the lower portion 51 of the action is forked or 30 bifurcated at 52, and the key-carriage is fitted with a screw-threaded stem 53 carrying spaced discs 54 adjustable thereon and adapted to engage above and below the fork or bifurcation. In a slightly modified 35 construction the discs 54 may be replaced by a spool adjustable on the screwed stem 53.

The means for "setting-off" the "jack" 30 may be varied. In Figures 12 to 14 the "setting-off" mechanism comprises a rocking plate 55 adjustably secured on the action rail 56, such as by means of two set screws 57, and carrying an arm 58 the covered end 59 of which serves as a "set-off". If desired, and as indicated in Figure 17, the "set-off" 59 of Figures 12 to 14 may be substituted by a hinged or pivoted piece 60 which inclines downwards towards the "jack" 30 and into a guide 61 formed or fitted on the ladder. With this construction, as the "jack" rises, the rounded end 62 of the hinged piece 60 moves into the portion 63 of the guide 61 and pushes the "jack" 30 forwardly so that the upper end of the "jack" is retracted and held in the 55 forward portion of the aperture in the manner above-described, thus preventing further raising of the action. In a slight modification of Figure 17 the hinged piece 60 thereof may consist simply of a piece of 60 wire, or it may have a wire projecting therefrom, and the guide 61 may be substituted by a hole formed in the "jack" and within which said wire engages. This wire may be screw-threaded and have one or more 65 pieces of wood or other suitable material

adjustably fitted thereon. When these means for positively operating and retracting the "jack" by the "set-off" are employed, the "jack" heel and spring usually utilized, such as indicated in Figures 12 and 13, may be dispensed with.

The sensitiveness of the damper 64 may be enhanced, and its operation positively ensured, by means of a thin wire spring 65 acting upon the damper-rod 66 through the 75 medium of a felt or other collar 67, said collar being adapted to slide on the said rod and thus provide a movable connection between the latter and the upper end of the spring.

The drawings illustrate the invention applied to actions for vertical pianos or instruments, but the invention is equally applicable to "grand" or horizontal pianos or instruments in which the strings are struck 85 from below or from above.

What I claim is:—

1. In a pianoforte action, a hammer provided with a closed loop projection having an extended portion, a jack having a laterally offset finger to cooperate with said loop, said finger being directly and loosely arranged within the loop and operative to engage the upper portion of the loop when the jack is operated and to recede into the 95 extended portion of the loop when the jack is set off.

2. In a pianoforte action, a hammer provided with a closed loop projection having an extended portion, and a jack having a laterally offset finger to cooperate with said loop, said finger being directly and loosely arranged within the loop and operative to engage the upper portion of the loop when the jack is operated and to recede into the 105 extended portion of the loop when the jack is set off, said loop including a lower portion into which the finger of the jack recedes and engages to pull the hammer back to its normal position.

3. In a pianoforte action, a hammer provided with a closed loop projection of oval form, and a jack having a laterally offset substantially circular finger to cooperate with said loop, said finger being directly 115 and loosely adjusted within the loop said finger engaging the upper portion of the loop when the jack is operated and receding into an extended portion of the loop when the jack is set off.

4. A pianoforte action including a hammer, a jack, an operative connection between the jack and hammer and means for setting off the jack including a plate rocking about a bearing on the action rail for 125 adjustment, means cooperating with the respective ends of the plate to hold said plate in adjustable rocked position, and an arm integral with the plate to cooperate with the jack for setting off the latter.

5. A pianoforte action including a hammer, a jack, an operative connection between the jack and the hammer, and means for setting off the jack including a plate having a rocking bearing on the action rail and terminally formed with slots, screws passing through the slots and taking into the action rail for adjusting the plate on its rocking bearing, and an arm integral with the plate to cooperate with the jack for setting off the latter.
6. A pianoforte action including a hammer, a jack, an operative connection between the jack and the hammer, and means for setting off the jack including a plate hav-

ing a rocking bearing on the action rail and terminally formed with slots, screws passing through the slots and taking into the action rail for adjusting the plate on its rocking bearing, an arm projecting from the plate, a member carried by the free end of the arm and a guide carried by the jack with which said member cooperates.

7. A pianoforte action including a key-carriage, the key-carriage being fitted with spaced discs and an action unit having a forked portion to operate between said discs.

In testimony whereof I have hereunto signed my name.

FREDERICK WILLIAM WAGGETT.
